UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHT-FOCUSING APPARATUS.

Application filed June 30, 1922. Serial No. 571,966.

To all whom it may concern:

Be it known that I, CROMWELL A. B. HALVORSON, Jr., a citizen of the United States, residing at Lynn, county of Essex, State of Massachusetts, have invented certain new and useful Improvements in Light-Focusing Apparatus, of which the following is a specification.

My invention relates to the method of and means for adjusting the source of light for a projector and for rapidly replacing one source for another or a defective one for a non-defective one and insure that the new source will instantly find its proper 15 position in the optical system.

Motion picture machines and the like which have made use of an arc-light for projection are now, in a great many instances, using incandescent lamps instead 20 and as is well known the filament of such lamps breaks from time to time and unless some provision is made for quick replacement, annoying delay results. The delay results from the fact that the filament of 25 such lamps must be accurately positioned with respect to the optical system and since no two lamps have their filament in the same place, each individual lamp must be adjusted to bring its filament into proper position. Heretofore means have been devised 30 which involve the use of a removable lamp socket which may be withdrawn as a whole with the injured lamp just as a drawer is removed from its pigeon hole. The circuit

35 for the socket is closed by way of the bearings when the socket is slipped into place. Upon cursory consideration it might be thought that if the lamp is adjusted with respect to the socket up and down; and the

40 socket back and forth in the adapter; and from right to the left that this would supply all the adjustment necessary to bring the filament into proper position; but when it is considered that the lamp is sometimes 45 tilted it will be realized that the lamp as a whole must be tilted back to bring the filament into position. And that is not all. Provision must also be made for rotating the filament about the major axis of the

50 lamp to bring the plane of the filament at right angles to the major axis of the projector thereby presenting the greatest width of the filament to the condenser lens.

One of the objects of my invention is to provide an adapter capable of all such adjustments. 55

While all of these adjustments may be made in the lamp housing, it is not convenient to use the housing for such purposes and in fact when the machine is in operation it is impossible to use the housing for such purpose. Therefore separate stationary lamp setting equipment has been provided heretofore but which does not provide for the adjustment of the lamp by tilting it 60 until the filament plane is brought into proper position. Nor do they provide in addition means for adjusting the filament up and down. In any event the devices of the prior art are cumbersome and complicated being provided with reflecting mirrors and pivotal structures. 65

It is another object of my invention to provide a lamp setter or adjuster devoid of all such complications and which at the 70 same time provides for all the adjustments above indicated. By the provision of such an adjuster, the attendant may, while the motion picture machine is in operation, set in readiness a number of lamps for immediate use in the event that the lamp in operation burns out. Such adjustments, of course, can be just as conveniently made before the picture machine is started in operation. In any event, it is more convenient to 75 use the lamp setter than it is to adjust the lamp in the lamp housing. 80

I also provide other details of improvement tending to increase the efficiency and serviceability of devices of the above character. 85

The means by which the above ends are accomplished are hereinafter more fully set forth and claimed, reference being had to the accompanying drawings. 90

In the drawings, Fig. 1 is a perspective view of the lamp setter opened to receive a lamp and socket. In this figure the socket is also shown to one side with the lamp in position. Fig. 2 is a section in elevation 100 through the socket; Fig. 3 is a section through the projector housing showing the adapter and socket in position; Fig. 4 is a section of the socket but taken at right angles to the section of Fig. 2; Fig. 5 is a 105 top view of the adapter; Fig. 6 is a side

view of the same; Fig. 7 is a side view of the adapter with the socket in place and with the lamp in the socket.

Referring more in detail to the drawings 5 the socket, Figs. 2, 3 and 4, has a base 2. On the under side of the base there are two metallic contact strips 3 and 4, one on each side, which are ordinarily about $\frac{1}{2}$ or $\frac{3}{4}$ of an inch wide and from 1 to $1\frac{1}{4}$ inches 10 long and these strips have metallic connections as shown in Fig. 4 with metallic terminals 5 and 6 respectively which are engaged by the terminals of the lamp. The terminal 6 as shown is the central terminal under 15 which there is an adjusting set screw 7 for regulating the height of the terminal 6; the outer terminal 5 is made up of three sections *a*, *b* and *c*. The sections *a* and *b* are closed metallic rings which are held together by 20 means of bolts 7' and 8. It will be observed that the elements *a*, *b* and *c* form a universal joint structure, the element *c* having its upper and lower rims 9 and 10 chamfered. The elements *a* and *b* are provided with corresponding sloping surfaces 11 and 12. It 25 will be observed that element *c* is in the form of a split ring. The lamp 13 may be an ordinary Mazda motion picture lamp. The dotted lines in Fig. 2 indicate how the lamp 30 is held between the split ring *c* and the inner terminal 6. Obviously, therefore, the lamp 13 may be tilted in any direction and tightly clamped by screwing the bolts 7 and 8 which of course compresses the ring *c* 35 against the lamp terminal in the socket.

In the base 2 (Fig. 1) there is a set screw 14 for adjusting the socket with respect to the adapter 15 (Fig. 5) or with respect to the base of the lamp setter (Fig. 1). The adapter also has an adjusting screw 16 which has a circular groove at the neck of the screw that is engaged by the heel adjusting heel plate 17. This heel plate may be set forward or back to any desired extent and clamped in such position by means of the nut 18. On the surface of the adapter there is provided a pair of metallic contact plates 19 and 20 to which the source of current supply may be connected. These contacts are engaged by the metallic strips 3 and 4 on the under side of the base 2 (Figs. 1 and 4), when the base is slipped in place on the adapter as shown in Fig. 7. The distance that the base can be slid in the groove on the adapter and on the holder setter, as will appear, is determined by the head of the screw 14, (Fig. 7). The groove for the base is formed by the bottom and sides of the adapter and by the top strips 21 and 22 that are screwed to the top of the holder, a similar construction appearing on the holder, (Fig. 1). If it is found that the lamp is set too far to the left (Fig. 7) it may be brought toward the right by turning the screw 14 clockwise; or it may be set further back, to the left, by

turning the screw counterclockwise and pressing the socket back until the screw head strikes the heel plate 17. Obviously therefore by means of screws 14 and 7 (Figs. 4 and 7) the lamp may be set up or down and to the right or to the left (Fig. 7). Referring to Fig. 2, it will be seen that in the set screw 7 there is a helical spring 23 (see also Fig. 4) located between this screw 7 and the terminal 6, which spring serves to make the contact 6 a yielding contact so that the lamp may be rotated or tilted in the socket without breaking the electrical connection. This contact 6 has a downwardly projecting neck on the lower end of which there is a head terminal. The object of the head terminal is to prevent the spring 23 from throwing the terminal out of position when the lamp is removed. It will be observed that on one side of the groove in the adapter (Fig. 5) there is a spring 25 that maintains the socket snugly against the opposite side of the groove and which serves to prevent any play of the socket in the adapter.

It now remains to consider the lamp setter (Fig. 1). This setter may be made in the form of a metallic frame 24. It is provided with a groove similar to that provided in the adapter which groove is also for the purpose of receiving the lamp holder. To one side of this groove in the setter there is a spring 26 which also serves to take up any loose play between the socket and the setter frame and which therefore corresponds to the spring 25 (Fig. 5). On the upper side of the setter there is a horizontal strap arm 27 which is hinged as indicated and on the opposite side of the frame from the hinge there is a latch spring 28 which is used to latch arm 27 to imprison the lamp 13 when the socket 5 is in the lamp setter. In the frame opposite the arm 27 there is a V slot 29 and a corresponding V slot 30 in the arm 27 located diametrically opposite, which slots serve for sighting the filament to bring it into a given position with respect to the setter frame. Also on the sides of the frame there are provided a pair of windows, each opposite the other and each having a horizontal ledge from which the pins 31 and 32 project as shown. These pins and the ledges from which they rise serve for sighting the filament to place it in proper position with respect to the setter frame. It will be understood that the line of sight between the grooves 29 and 30 and the line of sight between the pins 31 and 32 are at right angles to each other. On the upper section of the setter frame there are two set screws 33 and 34. The longitudinal axis of the screw 33 lies in the same plane with the line of sight connecting the grooves 29 and 30 and the longitudinal axis of the screw 34 is in the plane connecting the tips of the pins 31 and 32.

32. By means of these set screws the lamp 13 may be tilted in either the V sight plane or in the pin sight plane. On the inside of the hinge arm 27 I have provided a tension 5 spring 35 which is so set as to press the lamp 13 toward either of the set screws 33 or 34 and which therefore serves to maintain the lamp against these set screws when socket and lamp are set in the lamp setter. Now it 10 is to be understood that the intersection of the V sight axis with the pin sight axis locates a point which we will call the optical point of the setter and which point has a peculiar relation to the point in the actual 15 optical system, which latter point we will call the actual optical point, and with respect to which latter the filament should be properly set in the lamp housing. This relation is such that if the filament is set in the 20 setter in a given position relative to the setter optical point, then when the base and lamp are transferred to the adapter in the lamp housing, the filament will be placed in the same relative position to the actual optical 25 point and vice versa. In order to obtain this relation the altitude of the setter optical point above the holder is identical with the altitude of the actual optical point above the adapter in the housing. Therefore, it is obvious 30 that with my invention any number of lamps may be adjusted with respect to their sockets and with respect to the optical point of the setter so that a lamp may be replaced in a moment in its proper optical relation to the actual optical system the instant that the 35 socket and its base are pressed home in the adapter. I therefore have provided a new and very efficient device which is especially adapted for use in connection with a new, 40 simple and effective lamp setter, by means of which a speedy effective preadjustment may be obtained for the actual optical system the preadjustment being obtained by reference to what may be termed a phantom optical 45 system, both systems having each a point namely the setter optical point and the actual optical point such that adjustment with reference to one results in a similar adjustment with reference to the other.
- 50 It will be seen that without the sighting elements on opposite sides of the setter, Fig. 1, it would not be possible to effectively determine whether the filament of the lamp 13 is at the proper height. One sighting element alone would be insufficient to determine 55 accurately the correct height of the filament. It will be seen further that the filament may be adjusted not only in two planes at right angles to each other but also up and 60 down with respect to the base 2, by means of the screw 7 and further along a line in the one plane parallel to the other plane or along the line of intersection of the two planes.
- 65 With the means that I provide a motion picture device may be maintained in efficient operation with one lamp setter, two bases, and two sockets since while the motion picture machine is operating a lamp may be adjusted and made ready for instant use in case 70 the lamp in use burns out.
- 75 While I have shown and disclosed my invention in connection with a specific form of construction it will be understood that I do not wish to be limited to this form inasmuch as in view of the disclosure variations of my invention may readily suggest themselves to others which would fall within the scope of the claims appended hereto.
- 80 What I claim as new and desire to secure by Letters Patent of the United States is:—
1. The combination of a lamp setter with a lamp and a universal joint socket for the lamp whereby the lamp may be tilted in the setter along either of two intersecting planes 85 and mechanical means for raising or lowering the lamp within the socket.
  2. In combination with a lamp setter a lamp, a ball and socket joint and means for binding said lamp to said ball and socket 90 after the lamp has been set through the medium of said setter and mechanical means for raising or lowering the lamp within the socket.
  3. In combination with a lamp setter, a lamp, a ball and socket lamp holder in said 95 setter for setting said lamp by tilting the lamp in said holder along either of two intersecting planes and mechanical means for raising or lowering the lamp within the 100 socket.
  4. In combination with a lamp setter, a lamp, a ball and socket lamp holder in said 105 setter for setting said lamp by tilting the lamp in said holder along either of two intersecting planes and means on said setter for tilting said lamp, and means on the setter for determining the proper adjustment of the lamp in said planes.
  5. In combination with an optical system, 110 a lamp, mounting means for said lamp, means for moving the lamp in one direction, means for moving the lamp at right angles thereto, means for rotating the lamp in one plane and means for rotating the lamp at 115 right angles to the first plane.
  6. In combination with an optical system, 120 a lamp, mounting means for said lamp, means for moving the lamp in one direction, means for moving the lamp at right angles thereto, means for rotating the lamp in one plane and means for rotating the lamp at right angles to the first plane, said last means involving a lamp setter.
  7. In combination with an optical system, 125 a lamp mounting means for said lamp, means for moving the lamp in one direction, means for moving the lamp at right angles thereto, means for rotating the lamp in one plane and means for rotating the lamp at 130

right angles to the first plane, said last means involving a lamp setter, said lamp setter including a lamp holder.

8. In combination with an optical system, 5 a lamp, mounting means for said lamp, means for moving the lamp in one direction, means for moving the lamp at right angles thereto, means for rotating the lamp in one plane and means for rotating the lamp at 10 right angles to the first plane, said last means involving a lamp setter, said lamp setter including a lamp holder and including sights for determining how much the lamp is moved in any direction.
- 15 9. The combination of a lamp setter, a lamp socket and an electric lamp, the socket comprising a universal joint, means on the setter for adjusting the lamp in either of two planes while the base of the socket re- 20 mains stationary.

10. A lamp setter comprising a frame provided with sighting elements in two inter-

secting planes, a carriage mounted to slide in said frame, a lamp socket upon said carriage comprising a universal joint adapted to receive a lamp and adapted to permit the lamp to be tilted along either of two intersecting planes, and means associated with said socket for raising or lowering the lamp within the socket.

25 11. A lamp setter comprising a frame provided with sighting elements in two intersecting planes, a carriage mounted to slide in said frame, a lamp socket upon said carriage comprising a universal joint adapted to receive a lamp and adapted to permit the lamp to be tilted along either of two intersecting planes, means associated with said socket for raising or lowering the lamp within the socket, and micrometer means for adjusting the carriage.

30 In witness whereof, I have hereunto set my hand this 28th day of June, 1922.

CROMWELL A. B. HALVORSON, JR.
